UNITED STATES PATENT OFFICE

RAYMOND R. RIEHLE AND JOHN B. PEALLER, OF MILFORD, OHIO

FOOT CORRECTIVE SANDAL

Application filed September 22, 1931. Serial No. 564,388.

This invention relates to a foot corrective sandal adapted especially for the purpose of straightening toes and correcting other associated foot troubles.

5 Another object of the invention is to provide such a device which may be worn within the home and at night for correcting pedal malformations.

Another object is to provide such corrective 10 sandal which holds deformed toes in a normal position during the whole period in which the sandals are worn.

Another object is to provide a device of this 15 kind which is adjustable for use with various kinds of malformations and which may be adapted for use by various people.

Another object is to provide corrective 20 sandals of the class described which are simple in manufacture and readily adjusted to the feet of the wearer. These and other objects are attained by the means described herein and disclosed in the accompanying drawing, in which:

Fig. 1 is a perspective view of the sandal 25 with various foot corrective means of the present invention applied thereto.

Fig. 2 is a cross-sectional view taken on the line 2—2 of Fig. 1.

Fig. 3 is a perspective view of a modified 30 form of the sandal.

Fig. 4 is a cross-sectional view taken on the line 4—4 of Fig. 3.

Fig. 5 is an isometric view in longitudinal 35 cross-section, of another modified form of the sandal.

The device of the present invention 40 comprises briefly a rigid sole member having a counter attached at the rear and provided at the front end with a plurality of strap guides 45 adapted to embrace between each pair thereof a toe of a foot positioned upon the sandal. The strap guides are so disposed and spaced that each pair thereof embraces one of the toes of a normally formed human foot placed 50 upon the sandal. Through the strap guides, a strap is passed and formed into loops adapted each to embrace a toe. The strap ends are then tightened and returned over the toes of a positioned foot and secured thus 55 for maintaining misformed toes in proper

normal position during the period in which the sandal is worn. It will be understood that after often repeated periods of use the toes resume their proper normal shape. In connection with the foot sandal thus briefly described, other foot-corrective means will be set forth in the specification that follows.

With reference to the drawing: The sandal as shown in Fig. 1 comprises an upper and a lower rigid sole member 1 and 2 respectively, 60 which may be formed of wood plates conforming generally to the shape of a sole of a human foot, and joined together such as by glue or the like. The bottom member 2 is preferably formed to provide a heel portion 3, and a sole portion 4, the latter being suitably beveled as at 5 to permit a natural rise of the foot during walking. Before joining of the members 1 and 2, the latter may be covered with leather 6 which has its edges turned in between the joined sole members. Likewise, before joining of the sole members, six strap guides 7 are inserted through the upper member 1 adjacent the front thereof, the strap guides being in the form of wire loops, 75 the inner ends 8 of which may be bent inwardly of shallow depressions 9 provided in the under face of top member 6. Strap guides 7 are so positioned and spaced that each pair thereof will substantially embrace 80 one of the toes of a normally formed human foot placed upon the sole member. For this purpose, the strap guides are disposed longitudinally of the sole member 1 and such that each is in substantial longitudinal alignment with an imaginary point at the middle of the rear edge of the sole member 1. A strap 10 is passed loosely through the strap guides 7 to form toe-receiving loops 11 adapted each to embrace tightly one of the toes of the foot. The ends of strap 10, after the toes have been inserted through the loops 11, are returned over the tops of the toes, brought firmly together, and secured together such as by a buckle 12. The toes are thus held in proper position by two forces, namely, the individual loops 11 and the joined end portions of the strap 10.

The heel portion of the foot is held in place 100 by a counter 13 which may be secured by the

insertion of its lower edge 14 between the joined sole members 1 and 2. An ankle strap 15 and a cooperating buckle 16 may be provided upon the upper edges of the counter 13. The same kind of covering material may be applied to the counter as has been utilized upon the sole members.

As illustrated in Figs. 3 and 4, the construction of the sandal may be modified by forming the sole member of a single piece 17 having its upper and lower faces formed substantially the same as the like surfaces respectively, of the sole members 1 and 2 heretofore described. In this instance, the strap guides 7 may have their lower ends 18 terminating in and bent inwardly of depressions 19 provided in the bottom of the sole member 17. The depressions 19, subsequent to positioning of the strap guides 7, may be filled with wood composition 20 or the like. A preferable method of positioning the counter 13, is to provide a continuous slot 21 around the edge of the heel portion of the member 17, said slot being adapted to receive the turned in bottom edge of the counter. The latter may then be secured in place by means of nails or brads 22 projecting downwardly through the sole member.

A further modification is set forth in Fig. 5. Herein, a sole member 23 similar to the sole member 17, is provided. The top face of member 23 is covered by a rigid metal plate 24, conforming to the shape of said face. In place of the wire strap guides heretofore described, integral strap guides 25 struck upwardly from the plate 24, are provided. At the rear, the plate 24 may be cut with a small offset as at 26 to neatly accommodate the counter 13, the lower edge of which is turned in under the plate 24 and secured thereunder by means of nails 26 which likewise serve to secure metal plate 24 in position. Before positioning of the metal plate, the latter may be suitably covered such as with leather or like material 27. At this point it may be remarked that, in all the modification herein described, the sole members may be covered with enamel or other suitable covering material in place of the leather.

In addition to the toe straightening means above described, the present invention provides for other cooperating means. In Fig. 1 the sandal is shown as provided with a strap 28 secured between the upper and lower sole members 1 and 2 and provided intermediate its ends with an apertured bunion-embracing pad 29. A cooperating strap and buckle 30 and 31 respectively are provided upon the opposite side of the sandal. When this bunion corrective means is utilized the cooperation with the loop 110 which receives the great toe of the foot, is especially beneficial. It is common in abnormal conditions of the foot, for the great toe to assume an overlapping relationship with the toe adjacent there-

to. The loop 110 serves to move the large toe so affected toward the adjacent edge of the sandal while the bunion strap 28, operative upon the outwardly deformed joint immediately behind the great toe, serves to urge this joint inwardly, so that between the toe loop and the bunion strap, the great toe is urged toward a normal straight position, it being understood that the adjustments can be periodically made tighter as the malformation is gradually overcome. As shown in Figs. 3 and 4, the ends of the bunion straps 28 and 31 may be inserted into slots provided for this purpose in the edge of the sole member 17, said ends being subsequently fixed in place by nails 32. In Fig. 5 the ends of said bunion straps are inserted and secured beneath the plate 24, slots 33 being provided at the edge of the plate 24 for neatly accommodating said straps.

In the various figures are shown forms of arch and metatarsal supports. In Figs. 1, 2, 3, and 4 the metatarsal support 34 and the arch support 35 are shown as preferably resilient pads having brads or pins 36 embedded therein and projecting outwardly of the bottom face of said pads whereby the latter may be readily inserted in the sole members and removed therefrom for purposes of re-insertion as the corrective requirements demand. Different sized pads may likewise be substituted as needs require. It will be seen that the metatarsal support is provided with a curved upper face while the metatarsal support 35 is provided with a rising curvilinear surface 36 terminating at its highest edge 37 which is disposed flush with the edge of the sole member upon the arch side of the sandal.

In Fig. 5 the arch and metatarsal supports, instead of being provided by separate members, are formed integral with the rigid plate 24. In this instance the plate, before positioning thereof, is stamped upwardly at the desired places to provide the metatarsal support 37 and the arch support 38. However, in place of the upwardly formed plate thus described, the resilient support pads above set forth, may be utilized by gluing them upon the upper surface of the plate 24.

The metatarsal and arch supports of this invention are particularly effective as used with the sandal described herein since a perfect positioning of the foot is assured whereby the greatest benefit from said metatarsal and arch supports may be drawn.

The means of this invention are simple, sturdy and efficient. They have a wide adaptability and adjustability and may be used for correction of one or all of the common malformations of the foot discussed herein.

What is claimed is:

1. A foot corrective sandal comprising a rigid sole member, a counter secured to the heel portion of said member and having an an-

- kle strap thereon, a plurality of strap guides disposed upon the upper face of the sole member and so positioned and spaced as to embrace between each pair thereof a toe of the 5 normal human foot, and a strap for passing loosely through said strap guides to form toe-receiving loops adapted each to be tightened about a toe inserted therethrough, the ends of the strap being adapted to be returned over 10 the toes of a positioned foot and secured together for holding the toes in normal position.
2. A foot corrective sandal comprising an upper and a lower rigid sole member individually covered and suitably secured together, a counter attached at the rear of said members by securing the bottom edge thereof between the sole members, an ankle strap on the counter, a plurality of wire strap guides 15 embedded in and projecting upwardly of the upper sole member and so disposed and spaced as to embrace between each pair thereof an individual toe of the normal human foot, and a strap for passing loosely through 20 said strap guides to form toe-receiving loops adapted each to be tightened about a toe inserted therethrough, the ends of the strap being adapted to be returned over the toes of a positioned foot and secured together for holding 25 the toes in normal position.
3. A foot corrective sandal comprising a rigid sole member, a counter at the rear of the sole member and having an ankle strap thereon, a plurality of strap guides positioned upon the upper face of the sole member and so disposed and spaced as to embrace between each pair thereof an individual toe of the normal human foot, a strap for passing loosely through said strap guides to form 30 toe-receiving loops adapted each to be tightened about a toe inserted therethrough, the end portions of the strap being adapted to be returned over the toes of a positioned foot and secured together for holding the toes in normal position, and 35 a bunion corrective strap secured to the sole member and adapted to extend over the foot, said corrective strap comprising a perforate pad portion for embracing the affected part and adapted to cooperate with the great toe 40 loop of said strap for effecting straightening and correction of said part.
4. A foot corrective sandal comprising a rigid sole member, a counter at the rear of the sole member and having an ankle strap thereon, a plurality of strap guides positioned upon the upper face of the sole member and so disposed and spaced as to embrace between each pair thereof an individual toe of the normal human foot, a strap for passing 45 loosely through said strap guides to form toe-receiving loops adapted each to be tightened about a toe inserted therethrough, the end portions of the strap being adapted to be returned over the toes of a positioned foot and secured together for holding the toes in normal position, a 50 bunion corrective strap secured to the sole member and adapted to extend over the foot, said corrective strap comprising a perforate pad portion for embracing the affected part and adapted to cooperate with the great toe 55 loop of said strap for effecting straightening and correction of said part.
5. A foot corrective sandal comprising a sole member, a rigid plate attached upon and covering the upper face of the sole member, a counter secured to the sole member and having an ankle strap thereon, a plurality of strap guides struck upwardly from the rigid plate and so disposed as to embrace between each pair thereof a toe of the normal human foot, and a strap for passing loosely through said strap guides to form toe-receiving loops adapted each to be tightened about a toe inserted therethrough, the end portions of the strap being adapted to be returned over the toes of a positioned foot and secured together for holding the toes in normal position.
6. A foot corrective sandal comprising a sole member, a rigid plate attached upon and covering the upper face of the sole member, a counter secured to the sole member and having an ankle strap thereon, a plurality of strap guides struck upwardly from the rigid plate and so disposed as to embrace between each pair thereof a toe of the normal human foot, said plate being formed to provide upwardly-rising portions serving as arch and metatarsal supports, and a strap for passing loosely through said strap guides to form toe-receiving loops adapted each to be tightened about a toe inserted therethrough, the end portions of the strap being adapted to be returned over the toes of a positioned foot and secured together for holding the toes in normal position.
7. A foot corrective sandal comprising a rigid sole member, means at the rear of the sole member for engaging the rear portion of a foot, a plurality of strap guides disposed upon the upper face of the sole member and so positioned and spaced as to embrace between each pair thereof a toe of the normal foot, a strap for passing loosely through said strap guides to form toe-receiving loops adapted each to be tightened about a toe inserted therethrough, and means for holding the strap in the tightened position.
- In testimony whereof, we have hereunto subscribed our names this 15th day of September, 1931.
